United States Patent Office

Des. 228,854
Patented Oct. 30, 1973

228,854

WALL RACK

Dorothee Maurer-Becker, Habsburger Platz 2,
Munich, Germany

Filed Dec. 8, 1971, Ser. No. 206,234

Term of patent 14 years

Int. Cl. D6—04

U.S. Cl. D6—131

Fig. 1

Fig. 2

Fig. 3

Fig. 4

Fig. 5

Fig. 6

FIG. 1 is a front elevational view of a wall rack, showing my new design;

FIG. 2 is a top plan view thereof;

FIG. 3 is a left side elevational view thereof;

FIG. 4 is a right side elevational view thereof;

FIG. 5 is a bottom plan view thereof; and

FIG. 6 is a perspective view thereof.

I claim:

The ornamental design for a wall rack, as shown.
